UNITED STATES PATENT OFFICE.

IRAM Z. MERRIAM, OF WHITEWATER, WISCONSIN.

DAMPER-REGULATOR.

SPECIFICATION forming part of Letters Patent No. 499,435, dated June 13, 1893.

Application filed February 17, 1893. Serial No. 462,758. (No model.)

To all whom it may concern:

Be it known that I, IRAM Z. MERRIAM, a citizen of the United States, residing at White-water, in the county of Walworth and State 5 of Wisconsin, have invented certain new and useful Improvements in Damper-Regulators; and I do declare the following to be a full, clear, and exact description of the invention, such as will enable others skilled in the art 10 to which it appertains to make and use the same, reference being had to the accompanying drawings, and to the letters of reference marked thereon, which form a part of this specification.

15 My invention relates to an improvement in damper regulators or devices by which the dampers or valves of a heating furnace may be adjusted from various parts of the house to which it is applied, and it consists of a peculiar construction and arrangement of belt and pulley mechanism more fully described hereinafter and pointed out in the claims.

20 Referring to the accompanying drawings: Figure 1 represents a diagrammatical view of a hot air furnace equipped with my improvements, and Fig. 2, a detail view of one of the pulleys used in my invention.

The reference letter *a* represents an ordinary hot-air furnace having the cold-air or 25 feed-duct *b*, and hot-air pipes *cc'*, all of which are of the usual or any preferred construction.

e, e' represents the respective dampers of the pipes *c c'* to each shank or spindle of 30 which is immovably secured the grooved pulleys, *d d'*. Over these pulleys a belt *f f'* passes, thence over the pulleys or guides *f²*, located at every point where a turn in the belt is made, and finally over the pulleys *g g'*, 35 located in some convenient place where easy access may be had, by the occupants of the house. The pulleys *g g'*, are also grooved and journaled on short shafts or trunnions *h'*. These are in turn immovably fixed to the 40 vertically extending base-board *h*, which I shall hereinafter term the "switch board." The switch-board *h* is secured against the wall of the room in which it is located and provided with a third pulley *i* of a construction 45 similar to that of the pulleys *g* and *g'*. Running over the pulley *i*, is a belt *j*, one

end of which is connected to the swinging lid *k'* of the cold-air duct and the other end to the damper or draft-door *k*. These connections are so made that when the door *k* 55 is opened lid *k'* will be closed and vice versa.

Fixed to each of the pulleys on the switch-board *h*, is an indicator *l*. By means of this arrangement the condition of the dampers can be ascertained immediately. For example, the belts and pulleys may be adjusted 60 so that when the damper in the hot-air pipes is opened, the indicator on the pulleys *g g'* will be horizontal, and when closed the indicator will register vertical. This manner of 65 indicating the condition of the dampers is used also in connection with the door *k* and lid *k'*. It will be essential to the successful operation of the invention that the pulleys on both the dampers and switch-board be 70 provided with means to prevent the belts from slipping, as it is obvious if the belts slip, the adjustment of the indicators as described above, will be destroyed and disastrous results will follow. To this end I form in the 75 groove of each pulley having a sharply defined depression or recess *m* fixed therein, and extending across the path of the belt, a bar *n*. The belt is passed in the depression under the bar, thence around the pulley as 80 usual. By this arrangement all slipping of the belt is stopped and the perfect operation of the invention insured.

From the foregoing description it will be 85 obvious that the particular arrangement herein described is not essential to the device and that various changes could be made without departing from the spirit and scope of my invention. For example: a switch board, with its appliances, could be located in every or 90 any of the rooms of the house, or that pulleys having control over the hot-air duct leading to a certain room, be placed in such room and the other rooms similarly fitted. On the other hand I wish to say that no claim is made to 95 the arrangement for operating the door *k*, and lid *k'*, as this is conceded to be old and well known.

What I do claim, however, and desire to secure by Letters Patent, is—

1. In a damper regulating device, the combination of a pulley connected to the damper,

a second pulley located apart from the damper, an endless belt passing over the two, a depression in the face of the pulleys, and a bar in the depression, said bar extending at right angles to the path of the belt, substantially as described.

2. A pulley for use in connection with dampers having a depression in its face, and a bar in the depression, said bar extending at

right angles to the path of the pulley, substantially as described.

In testimony whereof I affix my signature in presence of two witnesses.

IRAM Z. MERRIAM.
